UNITED STATES PATENT OFFICE.

ARTHUR BATES AND THOMAS BRIGGS, OF LEICESTER, ENGLAND, ASSIGNORS TO
UNITED SHOE MACHINERY COMPANY, OF PATERSON, NEW JERSEY, A CORPO-
RATION OF NEW JERSEY.

MACHINE FOR OPERATING UPON BOOTS AND SHOES.

1,105,605.

Specification of Letters Patent.

Patented Aug. 4, 1914.

Application filed July 2, 1909. Serial No. 505,601.

To all whom it may concern:

Be it known that we, ARTHUR BATES and THOMAS BRIGGS, subjects of the King of England, residing at Leicester, in the county 5 of Leicester, England, have invented certain Improvements in Machines for Operating Upon Boots or Shoes, of which the following description, in connection with the accompanying drawings, is a specification, like 10 reference characters on the drawings indicating like parts in the several figures.

This invention relates to machines for operating upon boots or shoes.

In particular the invention relates to a 15 machine for attaching welts which has especial utility in effecting the attachment of a welt or rand to the bottom face of a lasted boot or shoe.

The term "welt," as used hereinafter, is 20 intended to include within the scope of its designation various articles having the general characteristics of a welt, although not necessarily its usual functions, such as rands, imitation welts, etc.

25 An object of the invention is to provide an improved machine for attaching welts which may be operated to turn out both an increased quantity of work and a superior quality of work, which will require in its 30 operation less labor and attention on the part of the operator than known machines and which will effect an economy in the material used.

In certain classes of work it has been the 35 practice to attach a welt upon the marginal portion of the sole or upon the bottom face of the lasted shoe. As the welt is bent edge-wise to conform it to the outline of the sole or bottom to which it is to be attached, diffi- 40 culty has been experienced in causing the welt to assume the outline of the part to which it is attached where this outline changes its direction abruptly, as, for example, at the sharply curved portions of the 45 outline about the toe part of the sole or shoe.

The difficulty in causing the welt to conform to the outline of the part to which it is being attached in certain portions of said outline frequently results in unevenness of 50 attachment and in the production of work in which the welt does not project the required distance beyond the edge of the last at all points. Even when the welt is guided

to the attaching means by a guide which has been fixed in the proper relation to the 55 attaching means to give the desired projection of the welt it nevertheless often happens that the welt, owing to its resistance to bending in its own plane, will be drawn back from the edge of the last at some points, especially when approaching and withdrawing from the toe portion, and at other points will with difficulty be brought into proper position to be attached.

In known machines the welt is frequently 65 attached by metallic fastenings and the work is positioned with respect to a fixed welt guide by a gage which bears against the upper. As above suggested, these machines are frequently unsatisfactory in operation, 70 since they do not insure the projection of the welt beyond the edge of the last the required distance at all points, and if the gage and welt guide are so adjusted that the required projection is secured at the abruptly 75 curved portions of the last an excess of projection at other points will result, thereby necessitating considerable trimming to reduce the projection to the required amount.

In the preferred form of the invention 80 the difficulty in obtaining the required projection at all points is obviated by the provision of means for effecting a relative displacement of the shoe and welt in such manner that the tendency of the welt to crowd 85 in upon the shoe or to resist conforming to the outline at certain points may be neutralized or compensated for, and that the welt when attached shall project beyond the edge of the shoe at least to the required 90 extent throughout all parts of its outline. This result may be obtained by effecting a relative displacement of the shoe and welt when the latter is to be attached to parts where the outline changes its direction 95 abruptly and by maintaining the shoe and welt in substantially a uniform relation to each other while the welt is being attached to parts where the outline does not change its direction abruptly. In one aspect the invention may therefore be said to comprise means for attaching a welt to work, and means for effecting a relative displacement of the welt and the work during the attaching operation. Preferably the means for 100 effecting the relative displacement of the

welt and the work during the attaching operation is constructed and arranged to act automatically as different portions of the work are presented to the attaching mechanism, and in another aspect therefore the invention 5 may be said to comprise means for attaching a welt to work and means for effecting automatically a relative displacement of the work and welt as different portions of the work are presented to the attaching means.

In the preferred embodiment of the invention, means is provided for guiding the welt to the attaching means, and a gage or 10 guide is provided for locating the work with respect to the attaching means and the welt guide. More specifically therefore the invention may be said to comprise the provision in a machine of the class described of 15 means for effecting, preferably automatically, during the attaching operation, a relative adjustment of the welt guide and the work gage. In the illustrated embodiment of the invention in which the welt is to be attached to a lasted shoe, the shoe is 20 preferably supported upon a jack in such manner that the jack turns with the shoe. A convenient method therefore of obtaining the automatic relative displacement of the 25 shoe and welt at the desired predetermined points in the path of movement of the shoe past the attaching means is to effect such movement in timed relation to the turning of the jack.

When, as in the illustrated preferred embodiment of the invention, the relative displacement of the work and the welt is effected in timed relation to the turning of a jack upon which the shoe is mounted it is 30 advantageous that the turning of the shoe be substantially about an axis passing through the point where the insertion of the fastening takes place and in the preferred embodiment provision is made for 35 such turning of the shoe. Moreover, provision is preferably made in the construction of the jack for both angular and bodily adjustment of the shoe with respect to the attaching mechanism in such manner that 40 the attaching means which, in the illustrated embodiment, is a metallic fastening, is inserted always along the axis about which the shoe turns. Accordingly, a feature of the 45 present invention comprises the provision in 50 a machine for attaching a welt to a shoe, of a support for the shoe so constructed and arranged that the shoe may be moved with its carrier both bodily and angularly into different relations to the attaching mechanism 55 and that the vertical axis about which the shoe turns passes constantly through the point at which the fastening inserting 60 operation takes place and that the fastening is driven into the shoe along this axis.

65 A preferred construction, according to the

present invention, will now be described by way of example as applied to a loose nailing machine of well-known type, reference being had to the accompanying drawings, in which,—

70 Figure 1 shows in side elevation the parts of the machine with which the invention is immediately associated; Fig. 2 is a section on the line 2—2 of Fig. 1; Fig. 3 is a front elevation of certain of the operative parts 75 of the machine, the shoe being shown in section; and Fig. 4 shows a shoe to which the welt is partly attached.

The machine in which the invention is embodied may be of the type disclosed in 80 the United States Patent 490,624, January 24, 1893, to L. Goddu and to this patent reference may be had for a detailed description of parts herein illustrated but not described. The machine of the said patent 85 comprises a laterally swinging head which carries an awl 2 and a driver 4. Connected with the head to swing therewith is a race-way 6. The head is moved laterally after the awl has penetrated the work to feed the 90 work and then the awl is retracted and the head returned to its original position to bring the driver 4 into alignment with the hole made by the awl. The nail is then discharged from the raceway 6 into the driver 95 passage in the nose 8 from which it is driven by the driver into the hole formed for it in the work by the awl.

The machine is provided with a jack, 100 preferably of the type disclosed in the application of R. F. McFeely, Ser. No. 264,260, filed June 8, 1905, for Letters Patent on improvements in jacks for shoe machines. This jack is rotatably carried by the jack post 10 which is mounted to reciprocate vertically in an upstanding portion 12 of the machine frame 14. The jack post 10 may be raised and lowered by any suitable treadle 105 operated mechanism (not shown) to present the shoe 16 in position to be operated upon 110 or to move it out of such position.

The jack has provision for enabling the shoe to be moved lengthwise and to be tipped about axes extending lengthwise and laterally of the shoe in order that parts of the 115 shoe to which the welt is to be attached may be presented properly to the fastening inserting mechanism. A detailed description of the jack will not be attempted herein, in view of its disclosure in the application 120 above referred to, and in view of the fact that it will not be herein specifically claimed. It will be sufficient to state that the carrier 18 for the last pin and saddle is provided with lateral grooves 20 which receive piv- 125 oted guides 22 carried in a yoke 24 arc-shaped upon its lower side and arranged to slide in an arc-shaped guideway in a block or hub 26 whereby the shoe may be tipped about its longitudinal axis as hereinabove 130

suggested. The rocking of the shoe about transverse axes is limited by the stop 30 which is vertically adjustable.

The welt 32 passes through a guide 34 carried by a slide 36 adjustable in guides in the machine frame. While being attached to the shoe the welt extends between the foot plate or work abutment 38 of the machine and the shoe on the jack, as shown in Fig. 3. An auxiliary guide 40, fixed upon the machine frame, supports the free end of the welt and keeps it out of the way of the operator.

A gage or guide 42, shown as a frustoconical roller, is mounted upon the slide 44 which is movable toward and away from the shoe in a block 46 secured to the machine frame. The slide 44 has a pin-and-slot connection 48 with the block 46 to limit the extent of its sliding movement. To provide means for varying the extreme positions of the gage or guide 42 the block 46 is mounted to slide on a guide 50 attached to the machine frame, and can be secured in adjusted position on said guide by a screw 52 which passes through a slot in the block 46 and screws into the guide 50. The slide 44 is operatively connected with a cam 54 carried upon the block or hub 26 of the jack by means of a lever 56 pivoted at 58 upon the machine frame and carrying at its upper end a screw 57 threaded through it, said screw abutting against the rear end of said slide, the lower end of the lever 56 carrying a roller 60 that engages the said cam.

In the operation of the machine the shoe 16 is placed upon the jack and the welt 32 is placed in the welt guide 34 and through the auxiliary guide 40. The jack is then elevated to clamp the welt between the foot plate or abutment 38 and the marginal portion of the sole face of the shoe, and the edge gage or guide 42 bears against the upper of the shoe adjacent to the welt, usually in the neighborhood of the shank or waist of the shoe. At this time the gage or guide 42 is in its extreme rearward position which, in practice, is preferably determined by the pin-and-slot connection 48 of the slide 44 with the block 46 which supports the slide, although it will be understood that this position may be determined in other ways, as for example, by the shape of the cam 54. The machine is now started and fastenings or nails are driven through the welt and into the insole, thus attaching them together, the shoe being fed by the awl 2 between the successive nail driving operations. When the toe part of the shoe is reached the jack is rotated by the operator in order that the welt may be attached around the said part. This rotation of the jack brings the cam 54 thereon into engagement with the roller 60 on the lever 56, thus moving the lever and through it the slide 44 that supports the

gage or guide 42. The gage or guide 42 is thus forced forwardly in the machine and effects the relative displacement of the shoe 16 and the welt 32 for the purposes hereinabove referred to. Continued rotation of the jack moves the cam 54 out of engagement with the roller 60 and lever 56 and permits the gage or guide 42 to be returned to its retracted position either by the pressure of the work against it, or by the action of a spring or the like, by which time the welt 32 will have been attached around the toe part of the shoe.

It will be noted that the jack is so constructed and arranged that it turns about the jack post 10 which is so located that its extended axis passes through the point at which the nails are driven. In this construction, therefore, the jack post 10 always receives the direct blow of the driver regardless of the adjustment of the carrier 18 with respect to the post or with respect to the inserting mechanism.

Having described our invention, what we claim as new and desire to secure by Letters Patent of the United States is:

1. A machine of the class described having, in combination, means for attaching a welt to work by successively inserted fastenings, means for guiding the work, and means for causing said last mentioned means to operate during the attaching operation to effect a relative displacement of the work and the unattached portion of the welt transverse to the line of attachment.

2. A machine of the class described having, in combination, means for attaching a welt to work, means for presenting successive portions of the work to the attaching means, and automatic means for effecting a relative displacement of the work and the unattached portion of the welt transverse to the line of attachment as successive portions of the work are presented to the attaching means, said automatic means being controlled as to the time of its operation by the effect of a characteristic of the work upon the presenting action of said presenting means.

3. In a machine for use in the manufacture of boots and shoes, the combination with means for attaching a welt along the margin of a piece of work by successively inserted fastenings, of means operated automatically through the work for effecting a relative displacement of the work and the unattached portion of the welt transverse to the line of attachment.

4. In a machine for use in the manufacture of boots and shoes, the combination with means for attaching a welt along the margin of a piece of work by successively inserted fastenings, of means operating when predetermined portions of the contour of the work come to the point of operation for effecting a relative displacement of the work

and the unattached portion of the welt transverse to the line of attachment.

5. In a machine for use in the manufacture of boots and shoes, the combination with means for attaching a welt along the margin of a piece of work by successively inserted fastenings, of means operating in time relation to and by virtue of the turning of the work for effecting a relative displacement of the work and the unattached portion of the welt transverse to the line of attachment.

6. A machine of the class described, having in combination, means for attaching a welt to work, an adjustable welt guide and an adjustable work gage, and means controlled as to the time of its operation by contour changes in the work for automatically effecting the adjustment of one of said adjustable parts as predetermined portions of the work are presented to the attaching means.

7. A machine of the class described, having in combination, fastening inserting mechanism and means controlled by the position of the work with respect to said inserting mechanism for effecting a relative transverse displacement of the work and said mechanism as successive portions of the work are presented to said mechanism.

8. A machine of the class described, having in combination, means for attaching a welt to work and means controlled by the angular position of said work with respect to said attaching means for effecting a relative displacement of said work and the unattached portion of the welt as successive portions of

the work are presented to the attaching means.

9. A machine of the class described, having in combination, mechanism for inserting fastenings, a work gage and a work support rotatable to present different portions of the work to the inserting mechanism, and means controlled by the rotation of said work support for varying the position of said work gage with respect to the inserting mechanism.

10. A machine of the class described, having in combination, fastening inserting mechanism, a welt guide, a work gage and a rotatable work supporting jack and means operating in timed relation to the rotation of said jack for effecting a relative displacement of the work gage and welt guide in a direction transverse to the direction of movement of the work to vary the projection of the welt beyond the edge of the work.

11. A machine of the class described, having in combination, mechanism for inserting fastenings, a welt guide and a work gage, a rotatable jack for supporting the work, and means controlled by the rotation of said jack for varying the position of said gage.

In testimony whereof we have signed our names to this specification in the presence of two subscribing witnesses.
